DOUGLAS A. WILSON, OF PEORIA, ILLINOIS, ASSIGNOR TO ALTORFER BROS. COMPANY,
OF EAST PEORIA, ILLINOIS, A CORPORATION OF ILLINOIS

WASHING MACHINE

Application filed December 16, 1927. Serial No. 240,547.

This invention has reference to washing machines and it has for its principal object to improve that type of machine in which is embodied a centrifugal extractor for drying 5 the clothes and other materials, following the washing, bluing or rinsing operation.

The invention has for one of its objects to provide an extracting receptacle where the free water is removed from clothing and 10 other materials by centrifugal action and expelled from said receptacle at the upper end thereof; to provide an operating means adapted for rotating the receptacle in opposite directions, as desired, and to provide for 15 the circulation of preferably cold or non-heated air down through the receptacle, during its rotation in one direction, whereby to insure, through the operation of extraction and air drying, that the clothing and 20 other materials will be ready for the ironer, on removal from said receptacle.

The invention has for a further object to provide for such a receptacle a closure including a depending thimble-like member 25 for spreading the clothing and other materials therein; said member being a depository and distributor for air entering the receptacle to direct the same for proper circulation into and through the receptacle; means being provided on the closure to direct air into said member.

A further object of the invention is to provide the receptacle with a base, both of which are adapted for rotation in opposite directions, and each having air egress openings for the discharge of air caused to enter and be circulated through said receptacle, on the rotation of the receptacle in one direction; said base having a free motion on the bottom 35 of the receptacle with each initial reverse movement imparted thereto, whereby the openings in base and receptacle are off-set one to the other, when the receptacle is rotated in one direction and said openings caused to 40 register with each other when the receptacle is rotated in an opposite direction.

A still further object of the invention is in the manner of connecting the receptacle with the operating means and in the reversing 50 mechanism for said operating means.

Other and further objects will more fully appear from the following description.

That the invention may be more fully understood, reference is had to the accompanying drawings, forming part of this description, illustrating a preferred embodiment of the invention, in which:

Fig. 1 is an elevation, mostly in section, showing my extractor and dryer associated with the tub of a washing machine, dotted lines showing the closure for the extractor in elevated or open position;

Fig. 2 is a plan view of Fig. 1, partly in section, that part which is in section being as it would appear if taken on the line 2—2 Fig. 1;

Fig. 3 is an elevation showing the lower end of the receptacle and the base therefor;

Fig. 4 is a plan in section, as the same would appear if taken on the line 4—4 Fig. 3, and

Fig. 5 is a plan of the base for the receptacle.

Like characters of reference denote corresponding parts throughout the figures.

The machine includes a washing tub 1 and 75 an imperforate extractor and drying member 2, the latter being in the form of a receptacle to hold clothing or other materials. Both of these elements are supported in or by a suitable frame work, comprising in part a head 80 frame 3, a lower frame 4 and standards 5, only one of which is shown, and it is shown connecting the lower and head frames, and to that part of the latter which is formed as an annular ring 6. The tub 1 is provided with 85 the usual agitator or washing element 7 operated from a shaft 8 passing up through the bottom of the tub and adapted to receive its power from any suitable source. The receptacle 2 is removably and rotatably supported 90 next adjacent the body of the tub 1 and is preferably rotated from and by means located below the receptacle.

Supported on the ring portion 6 of the head frame 3, and adapted to be manually and circumferentially adjusted thereon, is an annularly formed housing 9, provided with a lower annular ring or flange 10, which is of sufficient depth to provide the inner wall of the chamber 11 for the housing and a depend- 100

ing apron to be seated within the ring 6 of the head frame and to have a bearing therewith when the housing is revolved. The upper wall 12 of the housing has an enlarged annular opening 13 therein. The opening formed by the ring or flange 10 is of sufficient diameter to provide for the reception of the upper end of the receptacle 2, and the rotation thereof within said housing 9. The upper end of the receptacle 2 is shown having a flange 14 turned outwardly and downwardly and presenting a curved upper edge 15. When the receptacle 2 is in operative position on the machine, the flanged upper end overlies the upper end of the flange 10 of the housing, whereby water which is caused to be expelled through centrifugal action from the receptacle, is caused to travel upwardly in the receptacle and expelled radially therefrom over the curved upper edge 15 of said receptacle and discharged into the chamber 11 in the housing 9. Such water is then discharged from the housing through a conduit 16, see Fig. 2, formed or provided in a radial extension 17 from the housing 9, and in communication with the chamber 11 therein. The upper surface of the extension may serve as a drain board and is swingable to different positions, so that water discharged from the extension 17 may be directed into the tub 1 or to different receptacles not shown, as desired. The opening 13 in the head wall of the housing 9 is of a diameter to allow for the placement and removal of the receptacle 2 therethrough, including the flanged upper end thereof, as will be understood.

Arranged to normally overlie cross-wise the housing 9 is a support 18 hinged at 19 to one side of the housing whereby it may be lowered into closed position, as shown in full lines in Fig. 1 and raised to open position, as shown in dotted lines in said Fig. 1. For locking the support 18 in closed position I provide the member 20 which is pivoted, whereby it may be moved over said support and have a bearing relation thereagainst.

Rotatably supported on said support 18 is a closure or cover 21 for the upper end of the receptacle 2. The under peripheral edge portion of said closure is provided with a curved face 22 complementary to the curved upper edge 15 of the receptacle 2, and when closed has an impinging relation therewith so that as the receptacle is rotated, its closure will be rotated also. Said closure is formed or provided with the multiplicity of radially arranged water discharging outlets or openings 23. These may be provided, by being cut into the surface of the closure or be formed by corrugating the surface of the closure, as may be desired. The head wall of the closure may have a central bearing portion 24 surrounded by a plurality of inlet openings 25, preferably vertically disposed

with the walls forming the upper inlet ends tapered downwardly and outwardly, as shown in Fig. 1, for the induction of preferably cold or non-heated air into the receptacle. These openings at their lower ends open into and have communication with a chamber 26 formed or provided in said closure. This chamber 26 is preferably provided by constructing the closure in two sections, that which has just been previously described, and a lower section 27, removably secured thereto, by means of screws 28. Said section 27 having a depending thimble-like portion 29, the wall of which is provided with a multiplicity of air discharge openings 30, and said thimble-like portion 29 communicates with a radially arranged air conduit 31 which is in communication with a throat 32 from the chamber 26 from the main section of the closure. Thus it will be seen that air entering or being drawn down through the openings 25 will be caused to circulate to and through the throat 32 into the conduit 31 and thence into the thimble-like portion 29 and from thence through the openings 30 down into and through the receptacle 2, as will more fully appear.

The bearing portion 24 of the closure contains a self aligning ball bearing 33 providing a journal bearing for a short shaft or spindle 34 which is carried by the support 18 and passing into the chamber 26 of the closure has secured thereon and within said chamber a stationary pump element 35 formed or provided with the plurality of curved radially arranged wings or vanes 36, see Fig. 2. It is to be understood that the housing 9 and the support 18 are normally stationary, but capable of manual adjustment circumferentially of the extractor, but the closure is rotatable on the shaft or spindle 34, being rotated with and by the receptacle 2, whereas the pump element 35 is held stationary, air entering through the openings 25 being accentuated and accelerated by the rotation of the said receptacle, the wings or vanes 36 being curved in a direction to facilitate the travel of the air, resulting from the direction of rotation of the receptacle. The thimble-like portion 29 from the closure 21 being tapered downwardly and inwardly and depending sufficiently into the receptacle 2, when the closure is in position on the receptacle, to cause a uniform spreading of the clothing or other materials placed therein.

The lower end of the receptacle 2 is preferably tapered downwardly and inwardly, as at 37 and such tapered bottom portion is provided with air exhaust openings 38. The lower end portion of said receptacle is supported and carried within a base 39, conforming in shape to said lower end of the receptacle and the same is provided with air exhaust openings 40, adapted under certain operating conditions to register with the ex-

haust openings 38 and under certain other operating conditions to be in non-registered position therewith, or off-set thereto. This is brought about by allowing free movement 5 of the base 39 on the receptacle, with each initial rotation of the base and receptacle, when starting the rotation of base and receptacle in different directions. Such free movement of the base is a limited movement, and is 10 accomplished by slotting the base 39, at 41, see Figs. 3 and 4, for a predetermined distance and providing screws 42 passing through said slots and secured in the wall of the receptacle. Motion is imparted to the receptacle 2 15 through the base 39, and with each initial movement imparted to the base 39, in either direction the base will have a limited free rotation until an end wall of one of the slots engages with a screw 42, when the receptacle 20 is caused to rotate in unison with its base. Rotating the base in one direction will cause the air exhaust openings 40 and 38 to register, as in Fig. 1, whereas when rotating the base in the opposite direction will cause the air exhaust 25 openings 40 and 38 to assume non-registered or off-set positions, suitable packing 43 being inserted between the tapered surfaces of base and bottom of the receptacle preventing leakage.

30 The base 39 is provided axially with a depending hub 44 having a seat conforming to and adapted to have a slip on and off clutch connection with the upper end of a vertically disposed operating shaft 45 journaled at its 35 upper and lower ends in a housing 46 forming a part of or secured to the lower frame 4. Having a spline and groove connection with said shaft and slidable thereon is a sleeve 47 and to the opposite ends of said sleeve are 40 connected, to move therewith, bevel gear wheels 48 and 49 respectively, the latter having a grooved sleeve 50 with which is connected the yoke of a lever arm 51 fulcrumed at 52, and to said lever arm 51 is connected 45 an operating rod 52' which may lead to any convenient point on the machine to enable its operation by an attendant to move the sleeve 47 on the shaft 45 and control the direction of rotation of the receptacle. The 50 gear wheels 48 and 49 are adapted to be alternately moved into operation with a driving bevel gear wheel 53 on the inner end of a driving shaft 54 adapted to receive its power from any suitable source, and preferably 55 from the same source of power for operating the shaft 8.

To insure a proper frictional engagement between the base 39 and the lower end of the receptacle, I provide a stem 55 threaded into 60 the base and extending up through the bottom of the receptacle and thereinto and on said stem, within the receptacle, I provide a coil spring 56 the tension of which is regulated by a nut 57, holding the spring therebetween and the bottom of the receptacle. A

removable cap 58 covers the spring and its stem, as shown.

In the position the gearing is shown in Fig. 1, the receptacle 2 would be rotated for drying, after the water extracting operation, in 70 which position of the parts, the air exhaust openings 40 and 38 are in registered position, in which position air circulating down in the receptacle will exhaust through said openings, as shown by arrows.

75 After each extracting operation of the receptacle, and when the rotation of said receptacle is reversed, the clothing or other materials will be caused to disentangle and separate and allow the free circulation of 80 air therebetween and down through the receptacle, resulting in an efficient drying, whereby such clothing and other materials may be removed from the receptacle ready for ironing.

85 Lifting the support 18 into the open dotted position shown in Fig. 1 will remove the closure 21 from closed to open position, as will be understood, and will permit the lifting out and removal of the receptacle, detaching 90 it from operative connection with the operating shaft 45, as will be understood.

I prefer to use cold or non-heated air in the final step of drying because such an air, 95 it is found, will act to produce a fluffy velvety condition on the clothing or other material in preparation for the ironing of the same.

What I claim is:—

1. In a machine of the character described, 100 a receptacle for extracting water from clothing by centrifugal action, and to subsequently dry the clothing by the introduction of air thereto, means to rotate said receptacle in one continuous direction and while so rotated to extract water by centrifugal action and to discharge the same from the upper end thereof, means to alternately rotate said receptacle continuously in an opposite direction and means operable only when the receptacle is so rotated to induct air thereto and to cause a circulation of such air therethrough.

105 2. In a machine of the character described, an extracting receptacle arranged for the discharge of water at the upper end thereof, an operating means for said receptacle, means for reversing the direction of rotation of said operating means, and means to cause a circulation of air through the receptacle 110 and operable only during such reverse rotation thereof.

120 3. In a machine of the character described, an extracting receptacle arranged for the discharge of water at the upper end thereof, 125 an operating means for said receptacle, means to reverse said operating means to change, at will, the direction of rotation of said receptacle, a movable closure for said receptacle arranged when in closed position

to rotate with said receptacle, and means carried by said closure for introducing air into the receptacle on reversing the direction of rotation of said receptacle.

- 5 4. In a machine of the character described, an extracting receptacle arranged for the discharge of water at the upper end thereof, an operating means for said receptacle, means to reverse said operating means to change, 10 at will, the direction of rotation of said receptacle, a movable closure for said receptacle arranged when in closed position to rotate with said receptacle, means carried by said closure for introducing air into said receptacle during the rotation of said receptacle in one direction subsequent to the water extracting operation, and means to exhaust the air from the receptacle at the lower end thereof.
- 20 5. In a machine of the character described, an extracting receptacle arranged for the discharge of water at the upper end thereof, a reversible operating means for rotating said receptacle, at will, in reverse directions, 25 means to direct air into said receptacle at the upper end thereof during its rotation in one direction, and valved air exhaust outlets in the lower end of said receptacle, said outlets being alternately opened and closed during 30 the initial movement of said receptacle in opposite directions.

6. In a machine of the character described, an extracting receptacle, means to rotate said receptacle in opposite directions, a closure for 35 said receptacle adapted to rotate with the receptacle when in closed position, a movable support, means to journal said closure on said support, a chambered extension depending from said closure and having openings 40 in communication with the interior of said receptacle, and means on the closure arranged to conduct air to said chambered extension.

7. In a machine of the character described, 45 in combination, a frame, an extracting receptacle removably supported therein and adapted to discharge water therefrom at its upper end, an operating means arranged for driving connection with the lower end of said receptacle, means to reverse the direction of rotation of said operating means, a housing manually and circumferentially adjustable at the upper end of said receptacle and having a radially arranged discharge outlet, a 50 support hinged to said housing, a closure rotatably carried by said support and arranged to close the upper end of said receptacle and with said receptacle providing water exhaust outlets to discharge water into 55 said housing, means on the closure to introduce air into said receptacle as it is rotated in one direction, and means to exhaust air from the lower end of said receptacle during the 60 direction of rotation thereof when air is introduced therein, said air exhaust being

closed during the extraction of water and discharge thereof from the receptacle.

8. In a machine of the character described, 70 a receptacle for extracting water from clothing by centrifugal action, and to subsequently dry the clothing by the introduction of air thereto, means to rotate said receptacle in one continuous direction and while so rotated to extract water by centrifugal action and to discharge the same from the upper end thereof, and means to rotate said receptacle 75 continuously in an opposite direction and only while so rotated to induct cool or non-heated air thereto and to cause a circulation of such air therethrough.

9. In a machine of the character described, 80 a receptacle for extracting water from clothing by centrifugal action, and to subsequently dry the clothing by the introduction of air thereto, means to rotate said receptacle in one continuous direction and while so rotated to extract water by centrifugal action and to discharge the same from the upper end thereof, and means to rotate said receptacle 85 continuously in an opposite direction and only while so rotated to induct air thereto and to cause a circulation of such air therethrough, such air being introduced into the receptacle at a point below the upper end thereof.

10. In a machine of the character described, 90 an extracting receptacle arranged for the discharge of water at the upper end thereof, an operating means for said receptacle, means to reverse said operating means to change, at will, the direction of rotation 100 of said receptacle, a movable closure for said receptacle arranged when in closed position to rotate with said receptacle, and means carried by said closure for introducing air into the receptacle subsequent to the water extracting operation and arranged for the introduction of such air centrally below said closure.

11. In a machine of the character described, 110 a receptacle for holding clothing and to extract water therefrom by centrifugal action and to discharge the water at the upper end thereof, means to rotate said receptacle in opposite directions, and means to cause a circulation of cool or non-heated air 115 through the receptacle, only during the rotation of said receptacle in one direction and subsequent to and in a direction opposite to the water extracting operation.

12. In a machine of the character described, 120 a receptacle for holding clothing and to extract water therefrom by centrifugal action and to discharge the water at the upper end thereof, means to rotate said receptacle in opposite directions, and means to cause a circulation of air through the receptacle, only during the rotation of said receptacle in one direction and subsequent to and in a direction opposite to a water extracting 125 130

operation, such air being introduced into the receptacle at a point below the upper end thereof.

In witness whereof, I have hereunto affixed
my hand and seal this 12th day of December,
⁵ 1927.

DOUGLAS A. WILSON.
